UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,806, dated March 14, 1882.

Application filed February 11, 1882. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a large flower-group, consisting of full-blown roses supported on a cluster of leaves over a blank field, with projecting flowers and fern-leaves on all sides and leaf-clusters *a* and *b*, and two groups of circular flowers and buds, *c d*. Above A is a rectangular field, E, ornamented by small diagonal rectangular figures 15 with square centers. Below A is a rectangular field, F, ornamented by small diagonal squares with square centers, and partly traversed by leaf-clusters and flowers from adjoining groups and by the group B. B (shown in part at one 20 end and in part at the other end of the photograph) consists of a bouquet of roses and rose-buds, circular flowers, and geraniums, supported on a mass of fern-leaves, and with sprays of fern and flower traversing the surrounding 25 fields, the leaf-group *e* and flower-and-leaf group *f* traversing the upper parts of E and the lower parts of the adjacent fields G and H. G, an 30 irregular field ornamented by small squares, with squares at the corners and star-shaped centers, is partly traversed by sprays from ad-

jacent flower-groups. Above G and on the right-hand portion of the field F rests the flower-group C, which is a bouquet of roses and circular flowers with spreading ferns and a trailing stem below. It is shown in part on one 40 side and in part on the other side of the photograph. Above C is the irregular field H, covered with small ornamental squares having scrolls at the corners, and partly traversed by flower-and-leaf sprays. Above H is the flower-group D, resting chiefly on the left-hand portion of the field F. It is shown in part on one 45 side and in part on the other side of the design, and consists of a bouquet of roses and small flowers on a mass of leaves, with projecting 50 flower and stem and bud above and ferns on each side and drooping leaves below.

I claim—

1. The design for carpets, consisting of the fields E F G H, substantially as shown. 55
2. The design for carpets, consisting of the group B *e f*, substantially as shown.
3. The design for carpets, consisting of the group B *e f* and the fields E F G H, substantially as shown. 60
4. The design for carpets, consisting of the groups A B C D, *a b c d e f*, substantially as shown.
5. The design for carpets, consisting of the groups A B C D, *a b c d e f*, and fields E F G H, substantially as shown. 65

HENRY HORAN.
